UNITED STATES PATENT OFFICE.

JAMES L. JENKS, JR., OF MEDFORD, MASSACHUSETTS.

METHOD OF AND MEANS FOR ADJUSTING ROTARY SPARK GAPS OF WIRELESS APPARATUS.

Application filed February 11, 1922. Serial No. 535,814.

To all whom it may concern:

Be it known that I, JAMES L. JENKS, Jr., a citizen of the United States of America, residing at Medford, in the county of Middlesex and State of Massachusetts, have invented certain new and useful Improvements in Methods of and Means for Adjusting Rotary Spark Gaps of Wireless Apparatus, of which the following is a specification.

This invention relates to certain new and useful improvements in methods of and means for adjusting rotary spark gaps of wireless apparatus, and the invention has more particular reference to the provision of improved means for obtaining the correct tone for transmission in synchronous gaps employed in radio-telegraphy.

One of the most efficient spark gaps used in radio-telegraphy is the so-called synchronous gap. One form of synchronous gap very frequently met is that driven by a synchronous motor. In this type of synchronous gap the correct tone for transmission can only be obtained when the stationary electrodes of the gap are in the correct position relative to the rotating electrodes. This adjustment must be very close, i. e., within one or two degrees on the circumference of the discharge disk. In many gaps now being used the only method for obtaining the correct tone adjustment is to stop the synchronous gap and to change the position of the discharge disk with respect to the motor shaft, again starting the motor for another trial. In other words, it is impossible to adjust for tone or synchronism while the gap is rotating.

Since adjustment for synchronism must be made frequently, due to changing power condition on the line or in the transmitting transformer, some method of adjustment while the gap is rotating would be very useful. This condition is fulfilled by the present invention which preferably consists of an adjustable reactance in series with the stationary winding of the synchronous motor, the action of which is to cause the rotor, and hence the shaft to which the discharge disk is attached, to lag behind its normal position, the amount of lag depending upon the amount of reactance cut in.

Broadly stated, therefore, the invention consists in adjusting a synchronous gap by producing a lagging effect on the rotor of

the synchronous motor which drives the rotary electrode-carrying disk and while the gap mechanism is in operation.

With the above general objects in view and others that will become apparent as the nature of the invention is better understood, the same consists of the novel method and in the novel combination and arrangement of parts hereinafter more fully described, shown in the accompanying drawing and claimed.

In the drawing, wherein like reference characters designate corresponding parts throughout the several views,

Figure 1 is a diagrammatic view partly in plan and partly in perspective showing a portion of a wireless transmission apparatus equipped with one form of tone adjusting mechanism in accordance with the present invention,

Figure 2 is a diagrammatic view illustrating the lagging effect on the synchronous motor,

Figures 3 to 6 are developed diagrammatic views showing points on the cycle where the spark of a synchronous gap jumps or where it is broken,

Figure 7 is a view somewhat similar to Fig. 1 with parts removed showing a modified form of the invention,

Figure 8 shows a diagrammatic plan view of an adjustable air gap which may be employed in lieu of the adjustable reactance illustrated in Fig. 1.

Referring more in detail to the several views, and particularly to Fig. 1, the numeral 5 designates the feed wires from the main alternating current line, while 6 designates the rotor of the synchronous motor. This motor is here shown only in a semi-diagrammatic manner so as to disclose the relationship of certain parts and is provided with stator windings as indicated at 7, the windings 7 being connected at each side to a line wire 5 by means of further wires 8. An adjustable reactance generally denoted by the numeral 9 is placed in series with the stationary windings 7 as clearly shown in Fig. 1, this reactance being controlled by a single throw switch member 10 or the like whereby the desired amount of reactance may be thrown into circuit at will.

The rotor 6 is carried by a shaft 11 and this shaft also carries the disk 12 of the spark gap which has the usual plurality of

radial electrodes 13 adapted to cooperate in the usual manner with stationary electrodes employed at the points 14 as is usual, the stationary electrodes being in the oscillatory circuit 15 which includes an inductance 16, wires 17, a condenser 18 connected across said wires, and a high voltage transformer having a secondary 19 and a primary 20, the primary 20 being connected by means of wire 21 to the proper alternating current supply line.

The synchronous motor has the usual starting winding 22 which is connected directly across the line on the line side of the reactance 9 so that the adjustable reactance will have no effect upon said windings 22. It will also be noted that this starting winding is automatically cut out when the motor has come up to speed by means of a centrifugal switch diagrammatically illustrated at 23, and the starting winding is placed on the line side of the reactance, in order that the starting torque of the motor will not be weakened materially by the aforesaid reactance.

The reactance 9 embodies a plurality of contacts 24 connected by suitable wires at different points on the coil of the reactance and arranged in an arcuate manner so as to selectively cooperate with the adjacent end of the pivoted member 10, the arrangement shown being such that downward swinging movement of the member 10 will cut in more reactance and upward swinging thereof will cut out more of the same as found necessary to obtain the proper tone adjustment.

Referring to Fig. 2, the rotor 6 and the stator pole 7' are shown associated with dot and dash lines 25 and 26, which respectively indicate the position of the rotor with respect to the stator at a given point on the sine curve of the alternating current supply without any reactance in the circuit, and the position of the rotor with respect to the stator at the same point on the sine curve as above, but with a reactance in series with the stator windings of the synchronous motor, showing how the rotor lags behind its normal position.

In Figs. 3 to 6 the rotary discharge disk of the gap is indicated at 12 with the usual electrodes 13 cooperating with stationary electrodes at the points indicated at 14. The sine curve 27 is denoted in Figs. 3 and 5 with points 28 where the spark jumps and at 29 in Figs. 4 and 6 where there is no discharge, the jumping of the spark being shown as occurring at the peak of the curve at each side of the line 30.

By the above means, a change of position or lag of 10° or more on the circumference of the discharge disk is easily possible, and it is thus very easy to make all adjustments of tone while the gap is in rotation and to

make the adjustments very accurately and even at a remote distance if desired.

In connection with the adjustable reactance, several types are available, a closed core reactance with a tapped winding being probably the simplest to construct. As shown in Fig. 7, the windings of the stator itself might be made variable by simply connecting the stationary winding 7' at one side by means of a wire 8' to one of the line wires 5' and extending leads 31 from different points of the winding 7' to a series of contacts 32 cooperating with a single throw switch arm 33 which is connected to the other line wire 5' by means of a wire 8'. Also, a differently wound stator would probably prove more efficient with the external reactance control, i. e., a stator with greater torque to counteract the loss of power incidental to the use of external reactance.

An adjustable air gap would give a finer degree of adjustment, but would have less range. Such an air gap is shown in Fig. 8 and includes a core of reactance 34 adapted to be connected by wire 35 to the alternating current line and by wire 36 to the stator, a yoke or equivalent member 37 being associated with the core 34 and provided with means 38 for adjusting its position with respect to the core whereby the air gap between the member 37 and the core 34 is variable.

It is of course understood that the adjustable reactance and the variable air gap are commonly used for numerous purposes in electrical practice, but the specific application of the same in the radio-telegraphy art as set forth herein is believed to be new and to produce beneficial and new results.

From the foregoing description it is believed that the construction and operation of the device will be readily understood as well as its advantages appreciated by those skilled in the art, and it is noted that when the device is in operation the reactance may be varied so as to change the position of the rotor with respect to the phase of the line. The current lagging due to the added reactance makes the rotor lag behind normal, and this naturally gives a close and accurate adjustment of the synchronous tone of the gap and has the following advantages over adjustable stationary electrodes.

The clearance of the stationary electrode can be closely adjusted to the rotor, all tone adjustments being accomplished by the variable reactance, thus eliminating the danger of disturbing clearance adjustment when rotating the electrodes during operation.

In many enclosed synchronous gaps, adjustment for tone cannot be made during operation, but by the adjustable reactance method shown herein, very close tone adjustment can be obtained during actual operation.

The adjustment of tone can be remotely controlled by the adjustable reactance, eliminating all danger of shock to the operator and permitting adjustment of set 5 without leaving operating table.

It will be seen that the electrical principle involved in this invention will be found in either form shown in Figs. 1 and 7 or in Fig. 8, the particular means for obtaining 10 the result being the only difference.

Minor changes may be made in the invention without departing from the spirit and scope thereof as claimed.

What is claimed as new is:—

15 1. That method of adjusting a rotary synchronous spark gap which includes a rotary spark and is directly driven by a synchronous motor which consists in controlling the phase of the current supplied 20 to the motor and thereby regulating the discharge according to the spark gap.

2. In a radio apparatus, the combination with spark gaps including a rotary discharge

disk, a synchronous motor driving the discharge disk and having rotary and stator 25 winds, and a common alternating current supply for said gap and motor; of means for controlling the phase of the current supply to the motor and thereby producing lag in the motor with consequent lag in the spark 30 gap.

3. In a radio apparatus, the combination with spark gaps including a rotary discharge disk, a synchronous motor driving the discharge disk and having rotary and 35 stator winds, and a common alternating current supply for said gap and motor; of means for controlling the phase of the current supply to the motor and thereby producing lag in the motor with consequent 40 lag in the spark gap, said means including a variable reactance in series with the stator windings of the motor and means for manually adjusting said variable reactance.

In testimony whereof I affix my signature.

JAMES L. JENKS, JR.
